Term of patent 14 years

Int. Cl. D21—01

U.S. Cl. D34—5

FIG.1

FIG.2

FIG. 1 is a front elevation of a finger manipulative toy or similar article.

FIG. 2 is a plan view.

The device is symmetrical.

The characteristic feature of my design resides in the oblate spheroidal core in combination with ten cylindrical plungers radiating about said core in the particular arrangement shown.

I claim:

The ornamental design for a finger manipulative toy or similar article, as shown and described.
